(57) **CLAIM**

The ornamental design for a curved wall souffle dish, as shown and described.

DESCRIPTION

FIG. 1 is a top view of a first variant of a curved wall souffle dish, according to the present application;

FIG. 2 is a side view thereof;

FIG. 3 is a bottom view thereof;

FIG. 4 is a front perspective view thereof;

FIG. 5 is a top view of a second variant of a curved wall souffle dish, according to the present application;

FIG. 6 is a side view thereof;

FIG. 7 is a bottom view thereof;

FIG. 8 is a front perspective view thereof;

FIG. 9 is a top view of a third variant of a curved wall souffle dish, according to the present application;

FIG. 10 is a side view thereof;

FIG. 11 is a bottom view thereof;

FIG. 12 is a front perspective view thereof;

FIG. 13 is a top view of a fourth variant of a curved wall souffle dish, according to the present application;

FIG. 14 is a side view thereof;

FIG. 15 is a bottom view thereof;

FIG. 16 is a front perspective view thereof;

FIG. 17 is a top view of a fifth variant of a curved wall souffle dish, according to the present application;

FIG. 18 is a side view thereof;

FIG. 19 is a bottom view thereof;

FIG. 20 is a front perspective view thereof;

FIG. 21 is a top view of a sixth variant of a curved wall souffle dish, according to the present application;

FIG. 22 is a side view thereof;

FIG. 23 is a bottom view thereof; and,

FIG. 24 is a front perspective view thereof.

All side views of each variant, are identical.
